BOTTLE STERILIZING RACK

Joseph D. Kevorkian, Lansdowne, Pa., assignor to Advance Specialties Co. Inc., Lansdowne, Pa., a corporation of Pennsylvania

Application October 22, 1956, Serial No. 43,444

Term of patent 14 years

(Cl. D44—29)

I claim:

The ornamental design for a bottle sterilizing rack, substantially as shown.
